COMBINED FOAM BRUSH AND ADVERTISING CARD

Otto Mayer, R.F.D. 2, Lake Carmel, N.Y.

Filed Aug. 27, 1963, Ser. No. 76,372

Term of patent 14 years

(Cl. D9—2)

FIG. 1

FIG. 2

FIG. 3

FIG. 4

The fragmentary broken line showing of letters in FIG. 2 are for purposes of illustration only.

I claim:

The ornamental design for a combined foam brush and advertising card, substantially as shown and described.
